UNITED STATES PATENT OFFICE.

JOHN A. FERGUSON, OF BROOKLINE, MASSACHUSETTS.

DRIVING-BELT.

No. 841,680.

Specification of Letters Patent.

Patented Jan. 22, 1907.

Application filed February 20, 1904. Serial No. 194,495.

To all whom it may concern:

Be it known that I, JOHN A. FERGUSON, a citizen of the United States, and a resident of Brookline, in the county of Norfolk and State of Massachusetts, have invented an Improvement in Driving-Belts, of which the following description, in connection with the accompanying drawings, is a specification, like letters on the drawings representing like parts.

This invention relates to driving-belts, and particularly to belts of this class which are provided with means to counteract the stretching or elongating tendency of the material of the belt when in use.

Driving-belts, as ordinarily constructed of leather or fabric, soon become considerably elongated in use, owing to the necessity of drawing them tightly over the driving-pulleys with which they are used in order to give them the required gripping power and also owing to the strains incident to the load upon the pulley-shaft. This elongating and consequent loosening of the belt destroys in great measure its gripping power, whereby it is rendered comparatively useless until the slack is taken up by cutting out a section of the belt and reuniting the ends. This operation, however, involves time and expense, and, furthermore, the gradual attenuation of the belt is necessarily detrimental to the life thereof.

The character and scope of this invention will be clearly apparent from a description of one embodiment thereof, as illustrated in the accompanying drawings, in which—

Figure 1 is a plan view of a broken section of the belt, portions being removed to show the interior structure thereof. Fig. 2 is an edge view of the section shown in Fig. 1; and Fig. 3 is a transverse section on the line 3-3, Fig. 1.

In the embodiment of the invention herein selected for illustration the body of the belt is composed of the outer layers *a* and *b* of any suitable and desired material, preferably leather, and an intermediate layer or layers *c* of a non-stretchable material, in this instance so-called "fiber-board." Fiber-board is peculiarly adapted for use in this connection, for the reason that while it is absolutely

non-stretchable it is at the same time amply flexible to accommodate itself to the transversely-curved faces of the driving-pulleys, as well as to the constant flexing in passing around the latter. Furthermore, in the manufacture of fiber-board the pulp, which consists of some fibrous material—such as flax, hemp, or jute mixed with water—is so manipulated in the machine that the great mass of the fibers thereof are arranged in parallelism longitudinally of the pieces, which when cut in the direction of the fibers afford strips, which possess the greatest strength in the direction of strain when in use.

While a particular arrangement and number of layers of material has been shown and described, it is obvious that these details may be varied widely within the scope of the invention. The intermediate layer *c* may be arranged in any desired manner; but in the structure here illustrated it is composed of a plurality of strips extending in close proximity longitudinally of the belt. It is occasionally found to be desirable in practice, particularly in the case of short belts, to provide for a certain amount of stretch to allow of easy play of the belt over the driving-pulleys. To this end the non-stretchable layer *c* may be interrupted at intervals, as at *d*, and the space thus left may be filled, if desired, with any suitable material *x*, Fig. 2, preferably unattached to the adjacent ends of the layer *c*.

By employing a non-stretchable layer, as above described, it is obvious that inferior grades of material may be used to form the outer or friction layers *a* and *b*, and said layers, moreover, may be made up of a great number of short lengths pieced together.

Numerous changes may be made in the details and relative arrangement of the parts without departing from the spirit and scope of the invention.

I claim—

1. A belt comprising a ply of friction material and a ply made up of parallel strips of laterally-pliable but longitudinally-non-stretchable fiber-board.
2. A belt comprising a ply of friction material and a ply of non-stretchable material, the

latter arranged in a plurality of lengths leaving transverse spaces between the ends of adjacent lengths.

3. A belt comprising a ply of friction material and a ply of non-stretchable material, the latter arranged in a plurality of lengths leaving transverse spaces between the ends of adjacent lengths, and a filler for said spaces.

In testimony whereof I have signed my name to this specification in the presence of 10 two subscribing witnesses.

JOHN A. FERGUSON.
